UNITED STATES PATENT OFFICE

HAYMAN S. BASOW, OF BRYN MAWR, PENNSYLVANIA, ASSIGNOR TO RAPIDRYER MANUFACTURING COMPANY, INC., OF BRYN MAWR, PENNSYLVANIA, A CORPORATION OF PENNSYLVANIA

DRIER FOR TYPEWRITING MACHINES AND THE LIKE

Application filed March 27, 1931 Serial No. 525,689.

Typewriting machines, adding machines and other machines requiring repairs or renewals are frequently immersed in or otherwise cleaned with an appropriate fluid and thereafter have to be dried, an operation which heretofore required considerable time and in many cases resulted in the presence of rust spots on the machines.

The principal object of the present invention is to provide for drying such machines in a comparatively very short time and in such a way that rust spots are avoided.

To that and other ends hereinafter stated or appearing, the invention comprises a drier constructed, arranged and adapted for operation in the manner to be presently described and referred to in the claims.

In the following description reference will be made to the accompanying drawings forming part hereof and in which

Figure 1 is a front elevational view, principally in section, with parts removed.

Fig. 2 is a transverse sectional view.

Fig. 3 is an elevational view of the left-hand side of Fig. 1 with parts removed, and

Fig. 4 is a transverse sectional view taken on the line 4—4 of Fig. 1.

In the drawings 1 is a drying chamber provided with a door 2 and having openings 3 through its floor which communicate with the atmosphere. The chamber is shown as supported upon a frame 4. At the top of the chamber and in its back wall 5 is provided an opening 6 of substantially the width of the chamber and of comparatively small width in respect to the height of the wall 5 or, in other words, the opening 6 is narrow. 7 is a motor driven blower mounted below the chamber 1 and which is provided with a casing 8 having an intake 9. 10 is a housing enclosing the blower casing 8 and communicating with the inlet opening 9. 11 is a flue extending from the housing 10 upward past the chamber and it is open at its top at 12 for the intake of air. This flue includes an outward enlargement 13 at its upper part. 14 represents electric heating elements of which the number may be increased or diminished, and they project inwardly from the wall of the enlargement 13 of the flue. 15 is a baffle

plate extending from the wall of the flue opposite the enlargement, and it is arranged over the ends of the heating elements in order to deflect incoming air away from the hot ends of the heating elements and in that way prevent the incoming air from injuring or darkening them. There is a second flue 16 extending from the casing 8 of the blower past the chamber, and it communicates with the opening 6. 17 is a deflector for keeping the air entering the chamber 1 away from the hot ends of the heating elements 18 which project through the opening 6 and of which the number may be increased or diminished. Roof 19 of the chamber 1 is shown as inclined from the opening 6 downward and its purpose is to avoid space at the top of the chamber in which quiescent or dead air might accumulate, or, in other words, the roof 19 promotes uniform distribution of air passing through the chamber 1. Alongside of the flue 11 space is provided for a switch box 20, in which may be conveniently arranged switches for controlling the motor and the heating elements or groups of them. These switches and their connections require neither illustration nor description because they are well understood by those skilled in the art. The flue 16 is shown as constructed of two parts properly united by a coupling 22, and this is true of the flue 11 of which the parts are united by a coupling 21. The couplings are convenient in assembling and disassembling the device.

The operation may be described as follows:

The machine to be dried is placed in the chamber 1 and exposed to the uniformly distributed current of heated air by which it is dried in a few minutes in such a way that rust spots are absent. Air entering at 12 is deflected by the baffle plate 15 from direct impingement upon the ends of the heaters 14 and is heated by these heaters. The heated air passes through 11 into 10 and enters the lower casing 9 from which it is expelled by way of 16, and upon leaving the flue 16 it is deflected by the deflector plates 17 from direct impingement upon the ends of the heaters 18. The air is additionally 100

heated, and flowing past the roof 19 descends through the chamber 1 and escapes at the openings 3, and it is this current of air which dries the machine in the chamber 1.

23 is a movable pivotally mounted damper 5 and by adjustment it serves to deflect air to different parts of the chamber 1 as desired.

It will be obvious to those skilled in the art to which the invention relates that modifications may be made in details of construction and arrangement and matters of mere form without departing from the spirit of the invention which is not limited to such matters or otherwise than the prior art and the appended claims may require.

15 I claim:

1. A drier for typewriting machines and the like comprising a frame, a drying chamber carried by the frame and open at its lower portion to the atmosphere and having 20 at the top of its rear wall a narrow inlet opening of substantially the width of the chamber, a blower mounted below the chamber, a housing enclosing the blower, a flue 25 extending from the blower upward past the rear wall of the chamber and open at its top for the intake of air and having an outward enlargement at its upper part, electric heating elements projecting inward from the 30 wall of the enlargement of the flue, a baffle plate extending from the wall of the flue opposite the enlargement and overlying the ends of the heaters, a second flue extending from the outlet of the blower past the rear 35 wall of the chamber and communicating with said inlet opening, heaters projecting inward from the outer wall of the last named flue through said inlet opening, and a shield provided in the wall of the chamber 40 and projecting into the last named flue adjacent to the heaters.

2. A drier for typewriting machines and the like comprising a frame, a drying chamber carried by the frame and open at its lower portion to the atmosphere and having 45 at the top of its rear wall a narrow inlet opening of substantially the width of the chamber, a blower mounted below the chamber, a housing enclosing the blower and communicating with its inlet opening, a flue 50 extending from the housing upward past the rear wall of the chamber and open at its top for the intake of air and having an outward enlargement at its upper part, electric heating elements projecting inward from the 55 wall of the enlargement of the flue, a baffle plate extending from the wall of the flue opposite the enlargement and overlying the ends of the heaters, a second flue extending 60 from the outlet of the blower past the rear wall of the chamber and communicating with said inlet opening, heaters projecting inward from the outer wall of the last named flue through said inlet opening, a shield provided in the wall of the chamber 65 and projecting into the last named flue and pro-

jecting into the last named flue adjacent to the heaters, and an inclined roof for the chamber.

3. A drier for typewriting machines and the like comprising a frame, a drying chamber carried by the frame and open at its lower portion to the atmosphere and having at the top of its rear wall a narrow inlet opening of substantially the width of the chamber, a blower mounted below the chamber, a housing enclosing the blower and communicating with its inlet opening, a flue 70 extending from the housing upward along one side of the side wall of the chamber and open at its top for the intake of air and having an outward enlargement at its upper part, a switch box arranged at the side wall of the chamber beside said flue, electric heating elements projecting inward from the wall of the enlargement of the flue, a baffle plate 75 extending from the wall of the flue opposite the enlargement and overlying the ends of the heaters, a second flue extending from the outlet of the blower past the rear wall of the chamber and communicating with said inlet opening, heaters projecting inward from the outer wall of the last named flue through said inlet opening, a shield provided in the wall of the chamber 80 and projecting into the last named flue adjacent to the heaters, and an inclined roof for the chamber.
